UNITED STATES PATENT OFFICE.

WALTER W. YOUNG, OF PARKER, SOUTH DAKOTA.

BATTERY CARRIER.

Application filed June 2, 1922. Serial No. 565,425.

To all whom it may concern:

Be it known that I, WALTER W. YOUNG, a citizen of the United States of America, and resident of Parker, in the county of ⁶⁰ Turner and State of South Dakota, have invented certain new and useful Improvements in Battery Carriers, of which the following is a specification.

This invention relates to carriers, and has ¹⁰ for an object the provision of a novel handle and support, the latter of which is to be applied to an electric battery case to facilitate their manipulation in installing them in automobiles, removing them therefrom ¹⁵ and in transporting them to and from the storage room.

It is an object of this invention to produce a battery carrier of the character indicated which can be readily applied to or removed ²⁰ from handles or other hand grips or suspending means on batteries, or owing to the novel construction, the device can be applied to the eyes of terminals, or under the connecting straps of the battery, thus making ²⁵ it applicable for use in ninety per cent of the batteries now in common use.

It is a further object of this invention to produce a carrier of the character indicated, the hangers of which will adjust themselves ³⁰ to operative positions, practically regardless of the manner in which the handle is grasped.

It is a further object of this invention to produce a carrier of the character indicated ³⁵ which will possess advantages in points of simplicity and efficiency and which will, prove durable and satisfactory in use.

With the foregoing and other objects in view, the invention consists in the details ⁴⁰ of construction, and in the arrangement and combination of parts to be hereinafter more fully set forth and claimed.

In describing the invention in detail, reference will be had to the accompanying ⁴⁵ drawings forming part of this application wherein like characters denote corresponding parts in the several views, and in which—

Figure 1 illustrates a view in perspective ⁵⁰ of a battery carrier embodying the invention; and

Figure 2 illustrates a detailed view of one end of the handle.

In these drawings 5 denotes the handle ⁵⁵ bar which may be made of wood or other material, the ends of the handle being pref-

erably tapered slightly and provided with clips 6 which are secured to the handle by fastenings 7 such as rivets or the like. Each clip comprises a strip of material bent on ⁶⁰ itself to form a loop 8 which is intended to receive a hanger or bail 9, which bail is oscillatably applied to the loop in order that it will swing freely therein. Each bail is formed of a strip of material shaped to ⁶⁵ form a loop 10, whereas the ends of the material forming the hanger are inserted in a sleeve 11 located in a loop 8. The ends of the material forming the bail are preferably secured in the sleeve by solder or by welding, the manner in which this anchorage is ⁷⁰ effected being immaterial.

The bail has a swivel joint 12 applied to the loop 10, and the opposite end of the swivel is provided with tong-like elements ⁷⁵ 13 and 14 having angularly disposed ends 15 and 16, respectively, which are flattened and are adapted to lie parallel to each other when in position to engage the handles or other parts of the battery that is to be lifted. ⁸⁰

It will be seen that the elements 13 and 14 are capable of oscillatory movement on the lower end of the swivel and they may therefore be spread apart to form a clearance between their ends, in order that the ⁸⁵ said elements may be inserted under the straps of a battery, in the eye of a terminal, or otherwise manipulated to engage a part of the battery which will serve to support it ⁹⁰ while it is being transported.

As has been stated, the device may be manipulated so that when the handle is grasped, the bails may be thrown into operative positions by a slight movement of the hand of the user. The foregoing is rendered possible by the loosely jointed connections between the several parts of the device. ⁹⁵

As the bails are subject only to strain longitudinally, the material of which they are made may be comparatively light, so ¹⁰⁰ that the cost of producing the device will be small.

I claim:

1. In a battery carrier, a handle, a clip ¹⁰⁵ on each end thereof, a bail for each clip, each of said bails comprising a strip of material having a depending looped portion, a sleeve in each clip into which the upper ends of the material are inserted, the said sleeve being rotatable in the clips of the handle, and battery engaging devices supported by the bails. ¹¹⁰

2. In a battery carrier, a handle, a clip on each end thereof, a bail for each clip, each of said bails comprising a strip of material having a depending looped portion, and ends, the latter of which are supported by the clips, battery engaging elements comprising tong-like elements having angularly disposed extensions adapted to lie parallel with each other, and means for oscillatably supporting the said members from the bails.

3. In a battery carrier, a handle, a clip on each end thereof, a bail for each clip,

each of said bails comprising a strip of material having a depending looped portion, a sleeve to which the upper ends of the material are attached, the said sleeve being rotatable in the clips of the handle, battery engaging elements comprising tong-like elements having angularly disposed extensions adapted to lie parallel with each other, and a swivel interposed between and connecting the said members and a bail.

WALTER W. YOUNG.
